CLAIM

The ornamental design for a charging station, as shown and described.

DESCRIPTION

This application is related to co-pending U.S. design patent application Ser. No. 29/817,995, titled “Charging Station”, filed on Dec. 6, 2021, and is incorporated herein by reference.

FIG. 1 is a front perspective view of the charging station showing our new design;

FIG. 2 is a front view of the charging station shown in FIG. 1;

FIG. 3 is a rear view of the charging station shown in FIG. 1;

FIG. 4 is a left side view of the charging station shown in FIG. 1;

FIG. 5 is a right side view of the charging station shown in FIG. 1;

FIG. 6 is a top view of the charging station shown in FIG. 1; and,

FIG. 7 is a bottom view of the charging station shown in FIG. 1.

The broken lines shown in the drawings are for the purpose of illustrating portions of the charging station that form no part of the claimed design. References to “front,” “side,” “rear,” “left side,” “right side,” “top,” and “bottom” are not meant to require certain in-use orientation; a charging station according to the claimed design may be used in any orientation.

1 Claim, 6 Drawing Sheets
